[57] **ABSTRACT**

In a method of electrophotography wherein use is made of a photosensitive element including a highly insulative layer, a photoconductive layer manifesting persistent internal polarization, and an electrode layer transparent to visible light rays which are bonded together into an integral structure, and a latent image is formed on the surface of the highly insulative layer by depositing a charge of one polarity on the surface of the highly insulative layer and then depositing a charge of the opposite polarity concurrently with the projection of a light image through the transparent electrode, the highly insulative layer includes a mixture of a highly insulative material and a material highly reflective to visible light rays and the latent image is developed with a colored toner under ambient light while correcting the powder image by adjusting the density of the toner.

METHOD OF ELECTROPHOTOGRAPHY

CROSS REFERENCE TO RELATED APPLICATION

This application is a continuation-in-part of application Ser. No. 169,654 filed Aug. 6, 1971 now abandoned.

BACKGROUND OF THE INVENTION

This invention relates to an improved photosensitive element and a method of electrophotography utilizing the same in which the developed powder image can be observed while it is formed.

I have already invented a method of electrophotography as disclosed in U.S. Pat. Nos. 3,457,070 dated July 22, 1969 and 3,536,483 dated Oct. 27, 1970. According to this method an electrostatic latent image is formed by the steps of applying a first electric field across a photosensitive element including a transparent highly insulative layer, a photoconductive layer exhibiting persistent internal polarization and an electrode layer which are laminated in the order mentioned and bonded together into an integral structure whereby to deposit a charge of one polarity on the surface of the highly insulative layer; applying a second electric field across the photosensitive element to deposit a charge of the opposite polarity on the surface of the highly insulative layer; and projecting a light image on the photoconductive layer concurrently with the application of the second electric field whereby to form a latent image corresponding to the light image on the surface of the highly insulative layer. A second highly insulative layer may be interposed between the photoconductive layer and the electrode layer to improve the signal-to-noise ratio. Usually, the light image is projected upon the photoconductive layer through the highly insulative layer so that the highly insulative layer should be transparent to visible light rays.

The electrostatic latent image thus formed is then developed into a visible powder image under ambient light by means of colored (ordinarily black) toner, and the powder image is transfer printed onto a recording medium to produce a permanent copy. Due to large absorption of incident light rays by the photoconductive layer, the color thereof becomes black or deep red so that where the latent image is developed with black toner, it is impossible to observe or supervise the progress of development or the variation of color during the course of development because the light reflected by the photoconductive layer prevents such observation. For this reason, even though the method of electrophotography disclosed in the foregoing patents permits development and transfer printing under ambient light or uniform light, it is impossible to observe, correct or modify the progress of development to obtain valuable information or to use the developed powder image as a signal source.

SUMMARY OF THE INVENTION

It is an object of this invention to provide an improved method of electrophotography or radiation electrophotography in which the quality of the powder image can be readily controlled by adjusting the density of the toner while observing the powder image as it is being formed.

According to this invention there is provided a method of electrophotography comprising the steps of

preparing a photosensitive element including a highly insulative layer which includes a mixture of a highly insulative material and a material highly reflective to visible light rays, a photoconductive layer manifesting persistent internal polarization, and an electrode layer transparent to visible light rays, said layers being laminated in the order mentioned and bonded together into an integral structure; applying a first electrode field across the photosensitive element to deposit a charge of one polarity on the surface of the highly insulative layer; applying a second electric field across the photosensitive element to deposit a charge of the opposite polarity on the surface of the highly insulative layer; projecting a light image upon the photosensitive layer through the electrode layer concurrently with the application of the second electric field whereby to form a latent image corresponding to the light image on the surface of the highly insulative layer; developing the latent image with a colored toner under ambient light to form a powder image; and correcting the powder image during development by adjusting the density of toner while observing the powder image against the reflective background provided by the highly insulative layer.

According to another aspect of the invention, a powder image is formed by the same process steps as described hereinabove by using a modified photosensitive element in which a phosphor layer which emits visible light rays when excited by radiations such as X-rays or γ -rays from a radioactive substance, CO^{60} for example, is added on the side of the photoconductive layer opposite the highly insulative layer.

Since the highly insulative layer is highly reflective to visible light rays from the photoconductive layer, it is easy to observe, correct or modify the powder image throughout the course of forming the same. The resulting powder image may be transfer printed to obtain a permanent copy or can be used as an information source. Thus, for example, in the case of radiation electrophotography, the powder image may be photographed to produce a radiograph.

BRIEF DESCRIPTION OF THE DRAWING

In the accompanying drawing:

FIG. 1 is a diagram showing a cross-section of a portion of a photosensitive element embodying the invention;

FIG. 2 is a cross-section of a modified photosensitive element employing a phosphor layer; and

FIG. 3 is a graph showing the relationship between the percentage of reflectance and the quantity of TiO_2 incorporated into thin films of polyethylene terephthalate.

DESCRIPTION OF THE PREFERRED EMBODIMENTS

As shown in FIG. 1 the photosensitive element for use in electrophotography comprises a first highly insulative layer 1 which largely reflects visible light rays, a photoconductive layer 2 exhibiting persistent internal polarization, a transparent second highly insulative layer 3, a transparent electrode layer 4 and a transparent substrate layer 5 which are laminated in the order mentioned and are bonded together into an integral structure. Different from well known photosensitive elements, the first highly insulative layer is made of a highly insulative material of white, milky white or similar color and reflects visible light rays well. An example

of such material involves a mixture of a transparent synthetic resin, such as polyester resin, and a fine powder of crystals of metal compounds which reflect visible light rays such as PbO , TiO_2 , CaCO_3 and ZnS . The photoconductive layer 2 is made of a photoconductive material capable of exhibiting temporary persistent internal polarization. The material may be either an inorganic photoconductive material, such as CdS , ZnS , ZnO , PbO , ZnSe , Se , SeTe or an organic photoconductive material such as polyvinyl carbazol, anthracene and anthraquinone. Many other organic or inorganic photoconductive materials are known in the art. As has been described in said U.S. Pat. Nos. 3,457,070 and 3,536,483 according to the methods of these patents it is possible to use photoconductive materials having low dark resistance and high photosensitivity. The second transparent highly insulative layer 3 may be made of any organic or inorganic material having sufficient transparency and resistivity. It is essential that the highly insulative layer should not contain pin holes. The transparent electrode layer 4 may be made of a thin layer of SnO_2 or a vapor deposited film of gold having a thickness of about 100 $\text{m}\mu$. The transparent substrate layer 5 may be made of any transparent material such as glass or a synthetic resin.

A latent image is formed in the following manner by using the photosensitive element described above. Where the photoconductive layer 2 comprises a vapor deposited layer of selenium, since the polarity of the majority carriers of selenium is positive, in the first step, a first electric field is applied across the photosensitive element to uniformly deposit a positive charge on the surface of the highly insulative layer 1 by means of a removable electrode or a corona discharge unit. Concurrently therewith or after this sensitizing step, uniform light of suitable intensity is projected upon the photoconductive layer from the side of the transparent highly insulative layer 3 to stimulate the photoconductive layer with the light. However, such stimulation with light is not necessary where there are sufficient number of charge carriers in the photoconductive layer. In this manner, charge carriers are trapped in the layer of the photoconductive layer contiguous to the interface between the second highly insulative layer 3 and the photoconductive layer 2.

In the second step a second electric field is applied across the photosensitive element to deposit a charge of the opposite polarity on the surface of the first highly insulative layer concurrently with the projection of an information containing light image upon the photoconductive layer 2 from the rear or bottom side of the photosensitive element through transparent substrate layer 5, transparent electrode layer 4 and transparent highly insulative layer 3. At portions of the photoconductive layer corresponding to dark portions of the light image the charge carriers are trapped so that they cannot drift whereas at portions corresponding to bright portions of the light image the charge carriers are released and, since new electron-hole pairs are formed, charge carriers drift toward the first highly insulative layer. As a consequence, a charge pattern or an electrostatic latent image is formed on the surface of the first highly insulative layer. Since the latent image is formed on the highly insulative layer it will not be erased by later irradiation of light and can be retained and developed in a light area. As has been disclosed in the specification of U.S. Pat. No. 3,457,070 where the photoconductor contains deep trap levels as in the case

of ZnCdS:Ag or CdS:Cu it is advantageous to irradiate the photosensitive element with uniform light before development. The purpose of such post exposure is to depolarize persistent internal polarization caused by charge carriers trapped at the deeper trap levels and to extract the surface charge effect alone thus intensifying the apparent net surface charge.

The method of forming a latent image described above is generally analogous to those described in U.S. Pat. Nos. 3,457,070 and 3,536,483. The latent image formed by these prior methods are then developed with colored toners and transfer printed onto recording papers to obtain so-called hard copies. According to these prior methods, however, it is impossible to directly observe the latent image formed on the photosensitive element as an intermediate record or utilize it as a signal source for the following reason.

Where the photoconductive layer is required to have high photosensitivity and high resolution, the light absorption and hence the resolution of the photoconductive material should also be high. These characteristics are desirable for electrophotography. However, with such a material the color of the photoconductive material becomes dark or deep red by large absorption of visible light rays. When the latent image formed on the photosensitive element including a transparent highly insulative layer and a photoconductive layer of such characteristics is developed by means of a colored toner (ordinarily black) it is impossible not only to observe the intermediate steps of development but also to utilize the developed powder image as a source of information. For example where the evaluation of resolution or the concentration or contrast of the developed powder image is important as in the case of radiation electrophotography, whether it is possible or not to directly observe the progress of the steps of development determines the commercial value of the electro-photographic or recording system. These factors also contribute to the commercial value of the methods of aforementioned patents which enable development of the latent image under room light.

The invention is characterized by a photosensitive element for use in electrophotography capable of forming a latent image which can be directly observed or corrected during the course of forming it or can be used as a type of visible memory. More particularly, as described above, according to the invention the surface highly insulative layer 1 is made of an insulator which largely reflects visible light rays so that when the latent image formed on the surface of the highly insulative layer is developed by means of charged toner of black or dark color, it is possible to directly observe the developed powder image during the entire course of development without being disturbed by the color of the photoconductive layer. Where the developed powder image is used as a manuscript in an information transmission system, it is possible to suitably correct the powder image during the developing step to obtain a powder image of the desired quality. The powder image can also be utilized as a persistent but erasable visible image. Erasure of the powder image can be done by subjecting the photosensitive element to an AC field and then removing the toner. Such powder image can also be transfer printed onto a recording medium, for instance a sheet of recording paper, in a well known manner.

Correction of the tone or deepness of the color of the developed powder image can be made in the following

manner. Where the color is too deep the powder image is treated with a carrier alone to decrease the deepness to the desired level. On the other hand, where the color is too pale, the powder image is treated again with the colored toner. Since both dry type and wet type developing systems are not available, the term "powder image" herein used is intended to mean a visible image developed by either one of these two developing systems.

As shown in FIG. 3, the percentage of reflectance of thin films of polyethylene terephthalate varies with the content of a fine powder of TiO_2 incorporated in the films. A film of polyethylene terephthalate containing no TiO_2 was transparent, but to simulate the condition prevailing in the actual photosensitive element, thin films (each 12 μ thick) containing varied amounts of TiO_2 having a grain size of about 0.1 μ were placed on a layer of a black SeTe alloy and the percentage of surface reflectance of the respective films was measured with a Fujidensitometer sold by Fuji Photo Film Co. Ltd. Japan. The percentage of surface reflectance of a film containing no TiO_2 was 45% and increased with the content of TiO_2 . At a content of TiO_2 of 5% by weight the percentage of reflectance was about 80% and the film looked pale while at a content of TiO_2 of about 20% the percentage of reflectance approached 100%. From this and FIG. 3 it can be concluded that the addition of TiO_2 in amounts as low as 1% or 2% provide reflectances which are significantly improved over those of elements having no highly reflective material added to the insulative film. Reflectances from about 50 to 100% are useful in carrying out the present invention. Reflectances in the order of 80 to 100% are preferred, however, corresponding to additions of TiO_2 of about 5% by weight to more than 20%. Resins containing more than 20% of TiO_2 are difficult to be formed into thin films, however, and amounts of TiO_2 above 20% do not result in any additional advantage.

To determine the effect of the thickness of the film upon the degree of reflectance, films having thicknesses of 12 μ , 24 μ and 36 μ were tested and it was found that the percentage of reflectance is independent of the thickness of the film.

The following specific examples are given by way of illustration, and are not construed as limiting in any way the scope and spirit of the invention.

EXAMPLE 1

This example relates to a photosensitive element for use in radiation electrophotography. More particularly, as shown in FIG. 2, a phosphor layer 6 which, when excited by radiations, for example X-rays or γ -rays emitted by a radioactive substance, emits light of a wavelength in the visible range which can excite the photoconductive layer, is interposed between the electrode layer 4 and the substrate 5 of the photosensitive element shown in FIG. 1. Phosphor layer 6 can also be interposed between the photoconductive layer 2 and the second transparent highly insulative layer 3, or between the second highly insulative layer 3 and transparent electrode layer 4. As fully described in said patents, the purpose of using the second highly insulative layer is to improve the signal-to-noise ratio and use thereof is optional.

A fine powder of [ZnCd] S:Ag:Cl was homogeneously dispersed in a clear transparent synthetic resin binder and the mixture was coated upon substrate 5 to form the layer 6 having a thickness of 100 microns. The first

highly insulative layer 1 was made of polyester resin containing 20% by weight of a fine powder of $CaCO_3$. The photoconductive layer 2 was prepared by vacuum depositing a SeTe alloy whereas the second transparent highly insulative layer 3 was made of polycarbonate. Substrate 5 was an aluminum sheet having a thickness of 1 mm, which is transparent to radiations.

The photosensitive element was used in the following manner.

In the first step, uniform visible light was projected upon the photoconductive layer 2 through the first highly insulative layer 1 containing $CaCO_3$ to excite the photoconductive layer. Concurrently therewith, positive charge was uniformly deposited on the surface of the highly insulative layer by means of corona discharge as fully disclosed in U.S. Pat. No. 3,536,483. In the second step, while uniformly charging negative charge on the surface of the highly insulative layer 1 with corona discharge, an X-ray image of an object (not shown) was projected upon the phosphor layer 6 from the opposite side or through substrate 5. In response to the X-ray image the phosphor layer 6 emitted visible rays to excite the photoconductive layer 2 with a light image corresponding to the X-ray image, whereby a latent image was formed on the surface of the first highly insulative layer corresponding to the X-ray image. After a suitable time, typically a few seconds, the latent image was developed with a charged black toner. Since the first highly insulative layer 1 is white and does not transmit the light from the photoconductive layer 2, the developed powder image was very clear and it was possible to observe the detail thereof without the interference caused by the color of the photoconductive layer. By continuing the developing treatment the degree of blackness at black portions was increased. It was also possible to observe the detail of the portions of the powder image of intermediate tones by adjusting the tone of the powder image. Since the developing step was carried out in the bright or under room light, it was possible to fully observe the successive steps of development and to make necessary corrections. Thus, it was possible to obtain a powder image of the desired tone or bright-to-black ratio. During the course of development, or while the degree of blackness is increasing it was possible to obtain by observation much valuable information not obtainable with other types of photosensitive elements. Further, it was possible to transfer print onto a film or paper the powder image reproduced at an extremely high fidelity to obtain a permanent hard copy. After transfer printing, the toner remaining on the photosensitive element can be removed and the electrostatic latent image can be erased in a manner well known in the art for preparing the photosensitive element for use in the next cycle.

EXAMPLE 2

A latent image was formed and developed with the same photosensitive element and the same method as in Example 1. The powder image was used to form a second visible image through an optical system which may be an electrophotographic system or a video system. The powder image on the surface of the photosensitive element utilized as an intermediate record has an extremely high contrast. In addition, since it is possible to use intense light to illuminate the powder image, it is possible to produce a clear radiograph at higher efficiency than by photographing an X-ray image produced on a fluorescent screen of the conventional

X-ray photographic apparatus. Again the photosensitive element can be used repeatedly by erasing the powder image and the electrostatic latent image.

Although the above examples relate to radiation electrophotography, it should be understood that the advantage of the invention can also be obtained when a powder image of ordinary printed matter is formed by using the photosensitive element shown in FIG. 1. In such a case since the light image of the object is projected from the under side of the photosensitive element, all layers 3, 4 and 5 should be transparent to visible light. Whereas in the case of FIG. 2, layers 3 and 4 should be transparent to visible light, but substrate 5 is required to be transparent to radiations alone but not to visible light. Further, where phosphor layer 6 is interposed between layers 2 and 3 or between layers 3 and 4, those located between the photoconductive layer and the phosphor layer must be transparent to visible light whereas those located on the side of phosphor layer 6 opposite the photoconductive layer must be transparent to radiations. For this reason in the specification and claims the term "electromagnet wave" is used to mean either the radiations or visible light rays.

Further, the resinous material used to form the first and second highly insulative layers 1 and 3 may be any highly insulative material known in the art. Any inorganic or organic photosensitive photoconductive material exhibiting persisting internal polarization can be used to form the photoconductive layer 2.

What is claimed is:

1. A method of electrophotography comprising the steps of preparing a photosensitive element including a highly insulative layer which includes a mixture of highly insulative material and a material highly reflective to visible light rays, said mixture containing at least 5% by weight of said highly reflective material and said highly reflective material comprising fine crystals of metal compound reflecting visible light rays, a photoconductive layer manifesting persistent internal polarization and an electrode layer transparent to visible light rays, said layers being laminated in the order mentioned and bonded together into an integral structure; applying a first electric field across said photosensitive element to deposit a charge of one polarity on the surface of said highly insulative layer; applying a second electric field across said photosensitive element to deposit a charge of the opposite polarity on the surface of said highly insulative layer; projecting a light image upon said photoconductive layer through said electrode layer concurrently with the application of said second electric field whereby to form a latent image corresponding to said light image on the surface of said highly insulative layer; developing said latent image with a colored toner under ambient light to form a powder image; and correcting said powder image during development by adjusting the density of toner while observing the powder image against the reflective background provided by said highly insulative layer.

2. The method according to claim 1 wherein said metal compound is selected from the group consisting of PbO, TiO₂, CaCO₃ and ZnS.

3. The method according to claim 1 wherein said mixture contains from 5 to 20% by weight of said highly reflective material.

4. The method according to claim 1 wherein said photosensitive element further includes a second highly insulative layer transparent to visible light rays and

interposed between said photoconductive layer and said electrode layer.

5. The method according to claim 1 wherein uniform visible light is irradiated upon said photoconductive layer through said highly insulative layer concurrently with the application of said first electric field.

6. The method according to claim 1 wherein said latent image is irradiated with uniform light before development.

7. A method of radiation electrophotography comprising the steps of preparing a photosensitive element including a highly insulative layer which includes a mixture of a highly insulative material and a material highly reflective to visible light rays, said mixture containing at least 5% by weight of said highly reflective material and said highly reflective material comprising fine crystals of metal compound reflecting visible light rays, a photoconductive layer manifesting persistent internal polarization, an electrode layer transparent to electromagnetic waves, and a phosphor layer disposed on the side of said photoconductive layer opposite said highly insulative layer, said phosphor layer emitting visible light rays adapted to excite said photoconductive layer when irradiated with radiations, said layers being bonded together into an integral structure; applying a first electric field across said photosensitive element to deposit a charge of one polarity on the surface of said highly insulative layer; applying a second electric field across said photosensitive element to deposit

20 a charge of the opposite polarity on the surface of said highly insulative layer; projecting a radiation image upon said phosphor layer from the side thereof opposite said photoconductive layer concurrently with the application of said second field so as to cause said phosphor layer to excite said photoconductive layer with visible light rays whereby to form a latent image corresponding to said radiation image on the surface of said highly insulative layer; developing said latent image with a colored toner under ambient light to form

25 a powder image; and modifying the tone of said powder image during development by adjusting the density of toner while observing the powder image against the reflective background provided by said highly insulative layer.
